CLAIM

The ornamental design for a game board, as shown and described.

DESCRIPTION

FIG. 1 is a front left perspective view of a game board, showing my new design;

FIG. 2 is a top plan view of the game board;

FIG. 3 is a bottom plan view of the game board

FIG. 4 is a front elevation view of the game board;

FIG. 5 is a rear elevation view of the game board;

FIG. 6 is a right side view of the game board; and,

FIG. 7 is a left side elevation view of the game board.

The broken lines shown in the drawings depict portions of the game board that forms no part of the claimed invention.

1 Claim, 5 Drawing Sheets
